UNITED STATES PATENT OFFICE.

JOSEPH K. SIERER, OF NEW YORK, N. Y.

DESIGN FOR TILE COVERING FOR FLOORS, WALLS, OR OTHER SURFACES.

SPECIFICATION forming part of Design No. 36,234, dated February 24, 1903.

Application filed October 6, 1902. Serial No. 126,254. Term of patent 14 years.

To all whom it may concern:

Be it known that I, JOSEPH K. SIERER, a citizen of the United States, residing in the city and county of New York and State of New York, have invented a new, original, and ornamental Design for Tile Covering for Floors, Walls, or other Surfaces, of which the following is a specification.

My design is illustrated in the accompanying drawing, which shows a number of tiles having a trefoil shape united to form a floor or other covering, the marginal tiles being broken away. The shading in the drawing is for the purpose of conveniently illustrating the outlines of the individual tiles and not for the purpose of indicating color.

The essential feature of my design is the trefoil shape of the tiles composing it, the center foil of each being arrow-headed, with two double-tailed foils on either side growing from near the base or butt of the arrow-headed center foil.

I claim—

The new, original and ornamental design for tile covering for floors, walls and other surfaces, substantially as described and shown in the accompanying drawing.

JOSEPH K. SIERER.
